UNITED STATES PATENT OFFICE

1,975,090

DENATURANT FOR ETHYL ALCOHOL

Louis J. Figg, Jr., Kingsport, Tenn., assignor to
 Eastman Kodak Company, Rochester, N. Y., a
 corporation of New York

Application September 11, 1931, Serial No. 562,267

6 Claims. (Cl. 202—77)

This invention relates to the denaturing of ethyl alcohol, to compositions for use as denaturants and to alcohol so denatured.

It is an object of my invention to provide a denaturant which will render ethyl alcohol containing it unfit for use as a beverage, which cannot be economically removed from the alcohol by any known methods, which will not render the alcohol unfit for industrial uses in which completely denatured alcohol has customarily been employed, and which will be free from methanol. It is a further object of my invention to provide a completely denatured alcohol which will be free from methanol. Other objects will hereinafter appear.

I have discovered that certain oils produced in the purification of the liquid distillate from the destructive distillation of hardwoods may be freed from methanol by washing, and rectified to produce fractions which are very satisfactory denaturants for producing completely denatured alcohol.

The oils which I treat to produce my denaturants may be obtained as indicated in the accompanying flow sheet (Figure 1). Any hardwood materials may be used, but I prefer, for economic reasons, to use a mixture of hardwood forest waste and mill waste from hardwood saw mills. This hardwood is subjected to destructive distillation in oven retorts in known manner, to produce charcoal and a liquid distillate commonly known as pyroligneous acid. The pyroligneous acid is allowed to settle in settling tanks. At this point a tarry substance known as settled tar or insoluble tar settles out. The supernatant liquid is decanted off and distilled in a continuous rectifying still, which separates it into crude acetic acid and crude methanol. The crude methanol is then diluted with sufficient water to produce 30% methanol. It is at this point that the oils separate out which I purify and fractionate for use as denaturants, the oils separating by stratification and being decanted off from the 30% methanol.

It will be understood that I may vary the process by which these oils are obtained, the foregoing being merely illustrative. I may, in fact, obtain them at any suitable step in the purification of crude methanol by whatever method employed therefor.

These oils obtained in the purification of crude methanol are brownish, pungent liquids with an offensive odor and are insoluble or difficultly soluble in water.

One method of washing and fractionating these

oils is illustrated in the accompanying diagram (Figure 2). The oils are run into a wash tank; water is added to the oils, the mixture is vigorously agitated, and the two layers are allowed to separate. The oil layer separates out on top, while the water layer is drawn off at the bottom and discarded to the sewer. The washed oil, free from methanol, is then pumped into the kettle of the rectifying still. This still comprises a bubble-plate column, a dephlegmator and a condenser, and is provided with suitable tanks for receiving the oil fractions. Low-pressure steam is admitted to a heating coil in the kettle to furnish heat for the distillation. The oils distill over at from 41° to 230° C. The fraction distilling at 41° to 75° C. is cut to one of the receiving tanks, the 75—150° C. fraction to another, and the 150—230° C. fraction to a third tank. The fraction boiling at 75—150° C. is that which I prefer as a denaturant, although all three fractions are useful as such.

The purified oils (the middle fraction) thus obtained have a specific gravity of 0.860—0.880 at 15.6° C. They are soluble to the extent of 84% in a 5% sodium hydroxide solution. They are also soluble in acetone, methanol, methyl acetone, and methyl-ethyl ketone. They are unpalatable and have a very unpleasant odor even when highly diluted, and are soluble in ethyl alcohol in all concentrations necessary for denaturing.

As an ethyl alcohol denaturant, I prefer to use the fraction of these oils which distills at from 75° to 150° C. I may, however, use the fraction which distills at from 41° to 150° C., or I may collect the entire distillate, distilling at from 41° to 230° C., in one receiver, and use the whole distillate as a denaturant or I may employ a middle fraction starting at 41° to 100° C. and ending at 150° to 200° C. as will be apparent.

In denaturing alcohol with my new denaturant, I may add the oil directly to the alcohol. I prefer, however, for convenience in handling and accuracy in measuring, to dissolve the oil first in an organic solvent which is free from methanol and is miscible with ethyl alcohol, such for example, as acetone, and then to add the acetone solution of the oil to ethyl alcohol to produce a completely denatured alcohol. I have found that a mixture of my denaturant oil and acetone constitutes a denaturant for ethyl alcohol which cannot be removed economically by any known method.

Example.—25 cc. of the fraction of the denaturant oil which distills at from 75° to 150° C. is dissolved in 975 cc. of acetone. 50 cc. of this

solution is then added to a liter of ethyl alcohol to make a completely denatured alcohol. If it is not desired to employ the acetone, I may add from 1 to 2 cc. of this denaturing oil directly to one liter of ethyl alcohol. These proportions either with or without the acetone may be varied considerably as this oil is a powerful denaturant and therefore very economical.

It will be understood that I may vary the proportions of denaturant oil and/or of acetone without departing from the spirit or scope of this invention; that I may use another organic solvent in place of acetone, so long as it is free from methanol and miscible with both the oil and 15 ethyl alcohol, and that I may even omit the intermediate solvent altogether and add the denaturant oil directly to the alcohol. The omission of all methanol from my denaturant or from the denatured ethanol is not, of course, a matter 20 of necessity as the ethanol readily tolerates both. However, one advantage of my denaturant is that it is not poisonous and quite effective without methanol. Hence, ethanol denatured with my denaturant does not require the addition of other 25 substances and has the advantage of being wholly unpalatable yet nonpoisonous and suitable for commercial purposes without danger of being illegally diverted as the denaturant cannot be removed therefrom.

30 What I claim as my invention and desire to be secured by Letters Patent of the United States is:

1. A methanol-free denaturant for ethyl alcohol which comprises as an essential denaturing element, washed alcohol oil having a specific 35 gravity of approximately 0.86 to 0.88 and a boiling range from approximately 75° C. to 150° C. prepared by separating and distilling the major proportion of the oils contained in the crude aqueous-methanol fraction obtained from pyroligneous 40 crude resulting from hardwood distillation and condensing the fraction boiling between approximately 75° C. and 150° C.

2. A methanol-free denaturant for ethyl alcohol which comprises as an essential denaturing element, washed alcohol oil having a specific 45 gravity of approximately 0.86 to 0.88 and a boiling range from approximately 75° C. to 150° C. prepared by separating and distilling the major proportion of the oils contained in the crude aqueous-methanol fraction obtained from pyroligneous 50 crude resulting from hardwood distillation and condensing the fraction boiling between approximately 75° C. and 150° C., and a solvent for the oil which is miscible with ethyl 55 alcohol.

3. A methanol-free denaturant for ethyl alcohol which comprises as an essential denaturing element, washed alcohol oil having a specific gravity of approximately 0.86 to 0.88 and a boiling range from approximately 75° C. to 150° C. 80 prepared by separating and distilling the major proportion of the oils contained in the crude resulting from hardwood distillation and condensing the fraction boiling between approximately 75° C. and 150° C. and acetone. 85

4. Methanol-free denatured ethyl alcohol which comprises 1000 parts ethyl alcohol containing a denaturant comprising as an essential denaturing element, approximately 1-2 parts of washed alcohol oil having a specific gravity of 90 approximately 0.86 to 0.88 and a boiling range from approximately 75° C. to 150° C. prepared by separating and distilling the major proportion of the oils contained in the crude aqueous-methanol fraction obtained from pyroligneous 95 crude resulting from hardwood distillation and condensing the fraction boiling between approximately 75° C. and 150° C.

5. Methanol-free denatured ethyl alcohol which comprises 1000 parts ethyl alcohol containing a denaturant comprising as an essential denaturing element, approximately 1-2 parts of washed alcohol oil having a specific gravity of 100 approximately 0.86 to 0.88 and a boiling range from approximately 75° C. to 150° C. prepared by separating and distilling the major proportion of the oils contained in the crude aqueous-methanol fraction obtained from pyroligneous 105 crude resulting from hardwood distillation and condensing the fraction boiling between approximately 75° C. and 150° C., and approximately 49 parts of a solvent for the oil which is miscible with ethyl alcohol. 110

6. Methanol-free denatured ethyl alcohol which comprises 1000 parts ethyl alcohol containing a denaturant comprising as an essential denaturing element, approximately 1-2 parts of washed alcohol oil having a specific gravity of 115 approximately 0.86 to 0.88 and a boiling range from approximately 75° C. to 150° C. prepared by separating and distilling the major proportion of the oils contained in the crude aqueous-methanol fraction obtained from pyroligneous 120 crude resulting from hardwood distillation and condensing the fraction boiling between approximately 75° C. and 150° C. and approximately 49 parts acetone. 125
